CATHODE RAY TUBE

Otto Klemperer, Iver, England, assignor to Electric & Musical Industries Limited, Hayes, Middlesex, England, a company of Great Britain

Application July 30, 1938, Serial No. 222,210
In Great Britain September 11, 1937

2 Claims. (Cl. 250—27)

My invention relates to electron discharge devices of the cathode ray type and more particularly to cathode ray tubes having a fluorescent screen for the reconstitution of images such as used in television receiving systems.

5 Cathode ray tubes for television reception are usually provided with an electron gun for generating a beam of electrons and a fluorescent screen provided on the wall of the tube opposite the 10 electron gun which is scanned by the electron beam to produce fluorescent effects. It has been found in the use of such tubes that the intensity of the fluorescent effect is approximately proportional to the velocity with which the electrons 15 impinge upon the fluorescent screen and it is, therefore, desirable to use a high velocity electron beam in such tubes especially when the tubes are used in conjunction with an optical lens for projecting the fluorescent image upon a distant 20 viewing screen. Where such a high velocity beam is employed, it is found that the fluorescent screen charges up negatively since with a high velocity beam the ratio of the number of secondary electrons emitted by the screen to the incident 25 primary electrons impinging on the screen becomes less than unity. It is, therefore, necessary for the proper operation of cathode ray tubes employing high velocity beams to maintain the fluorescent screen at a highly positive voltage 30 or to neutralize the negative charge which is produced upon the screen by the high velocity electrons. It has been proposed to employ a thin translucent conducting film deposited on the end wall of the tube and beneath the fluorescent 35 material, which film is maintained at the desired positive potential. Considerable difficulties are encountered in producing a conducting film of this nature and even when such a film is properly applied, it is undesirable in that the light 40 output of the device is reduced because of the non-transparent properties of the film.

It is the principal object of my invention to provide a cathode ray tube wherein a high velocity electron beam is incapable of negatively 45 charging the fluorescent screen with respect to the surrounding electrode structure. It is a further object of my invention to provide such a tube in which the fluorescent screen is maintained at full operating positive potential.

50 In accordance with my invention, I provide a cathode ray tube employing a high velocity electron beam wherein a source of electrons of low velocity is provided which is positioned to direct a spray or substantially uniform flood of low 55 velocity electrons upon the fluorescent screen

to cause thereby the emission from the screen of a greater number of secondary electrons than incident low velocity electrons. Further in accordance with my invention, I provide an auxiliary source of electrons which are of such low 5 velocity as to cause negligible fluorescence on the fluorescent screen.

These and other objects, features, and advantages of my invention will appear from the following description taken in connection with the 10 accompanying drawing in which;

Figure 1 is a diagrammatic sectionalized view illustrating one form of a cathode ray tube incorporating my invention; and,

Figure 2 is a curve illustrating the operation of 15 the fluorescent screen shown in the tube of Figure 1.

Referring to Figure 1, a tube made in accordance with my invention comprises a highly evacuated glass envelope or bulb 1 enclosing at one 20 end a conventional type electron gun and at the opposite end a fluorescent screen 2 which is preferably deposited directly upon the flattened end wall of the bulb 1 so that it may be viewed directly through the transparent end wall. 25

The electron gun assembly is of the conventional type and comprises a cathode 3 from which an electron stream may be drawn, a control electrode 4 connected to the usual biasing battery 30 and a first anode 5 maintained positive with respect to the cathode 3 by a source of potential such as the battery 6. The electron stream leaving the first anode 5 is highly accelerated and concentrated into an electron scanning beam focused on the front surface of the fluorescent 35 screen 2 by a second anode 7. My invention is particularly useful where the final accelerating potential such as applied to the anode 7 by the battery 6 is equal to or greater than 10,000 volts. 40 For the purpose of deflecting the electron beam generated by the cathode 3 over the fluorescent screen 2, I provide electromagnetic coils 8 which are preferably located between the end of the anode 7 and the screen 2. It is obvious, however, that conventional electrostatic deflection plates 45 may be substituted for one or both of the deflection coils if desired.

The fluorescent screen 2 may be of any desired composition depending upon the desired color of fluorescence, and may be of calcium tungstate, 50 zinc sulphide, zinc silicate, or any other desired material. The fluorescent screen may likewise be deposited on the end wall of the bulb 1 by setting, spraying, dusting, or by any other desired method. 55

In accordance with my invention, I provide adjacent the fluorescent screen 2 but removed from the path between the electron gun and the fluorescent screen, an auxiliary source of electrons 5 which, as shown in Figure 1, may comprise a thermionically activated cathode 9 and an auxiliary anode 10 positioned between the cathode 9 and the fluorescent screen 2 and so arranged that the electrons liberated from the cathode 2 are 10 directed upon the fluorescent screen as a substantially uniform spray of low velocity electrons. The auxiliary cathode 9 in combination with the anode 10 may be termed as an auxiliary electron gun. The cathode 9 is maintained at a low negative potential, such as 200 to 400 volts with respect to the potential of the second anode 7, 15 preferably by a source of potential such as the battery 11. The anode 10 is preferably maintained at the same positive potential as the anode 20 7 and causes the electrons liberated by the cathode 9 to be continuously sprayed upon the fluorescent screen 2 at low velocity over the whole of the fluorescent screen with a substantially uniform intensity.

Referring to Figure 2 which shows the secondary emission response of a conventional fluorescent screen with respect to second anode potential, it is seen that at low potential on the second anode which corresponds to low electron beam velocity from the cathode 3 that the number of secondary electrons liberated from the fluorescent screen with respect to the number of impinging electrons is less than unity but that as the voltage on the second anode is increased, the curve rises to a point A where the number of secondary electrons liberated from the screen is equal to the number of impinging electrons. As the second anode voltage is increased still further the curve rises, indicating 40 an increased ratio of secondary to primary electrons and as the second anode potential is still further increased the curve crosses the point B where the number of secondary electrons liberated is equivalent to the number of impinging electrons. A cathode ray tube having a fluorescent screen secondary emission characteristic, such as shown in Figure 2, will operate quite satisfactorily for anode voltages between the values represented by the points A and B but 45 as the beam velocity is increased by increasing the anode potential beyond that represented by the point B, the fluorescence of the fluorescent screen does not materially increase because the fluorescent screen remains at the approximate 50 positive potential of the point B. If, however, the screen is bombarded by auxiliary electrons having a velocity corresponding to a potential between those potentials represented by the points A and B, additional secondary electrons will be 55 liberated from the fluorescent screen thereby increasing its potential in a positive direction notwithstanding the presence of the high velocity beam such as from the cathode 3 shown in Figure 1. It is desirable to maintain the velocity of 60 the electrons from the cathode 9 as low as is possible commensurate with satisfactory operation to limit the fluorescence generated on the fluorescent screen by these low velocity electrons. Thus, if the electrons from the cathode 9 are 65 accelerated such as by potential of 200 volts on the auxiliary anode 10 with respect to the cathode 9 and the potential existing between the cathode 3 and the second anode 7 is 20,000 volts, the low velocity electrons will produce approximately $\frac{1}{100}$ 70 of the light intensity produced by the high veloc-

ity beam. This low value of background light produced by the low velocity electrons is not overly objectionable and becomes even less objectionable with further increase of second anode potential.

Although my invention has been described above as being applied to a cathode ray tube suitable for use in television receiving systems, it is to be understood that the invention may be applied to other forms of electron discharge devices employing fluorescent screens such as electron telescopes, light transformers, and the like, without departing from the scope of the invention as set forth in the appended claims.

I claim:

1. A cathode ray tube and system comprising a tube having an electrically nonconducting screen base, an electrically nonconducting fluorescent screen on said base having a secondary electron emission ratio less than unity when impinged by electrons having a high electron beam velocity and a secondary emission ratio greater than unity at a lower beam velocity and an electron gun oppositely disposed from and wholly exposed to said screen, said gun comprising a cathode for generating an electron beam and an anode to focus said beam on said screen, a source of direct current potential connected between said cathode and said anode to apply a difference of potential sufficient to accelerate the electron beam to a velocity in excess of the electron beam velocity which produces a greater than unity secondary electron emission from said screen, means to scan said electron beam over said screen, an auxiliary cathode adjacent and directly exposed to said fluorescent screen but outside the path of said electron stream from said electron gun, an auxiliary anode between said auxiliary cathode and said screen to direct a stream of electrons to said screen along a path outside the path of said beam, a source of direct current potential less than the potential between said cathode and said anode connected between said auxiliary cathode and said auxiliary anode, said source being sufficient to produce electron velocities at which the secondary electron emission is greater than unity from said screen but insufficient to excite the screen to a luminescence more than a small fraction of the luminescence produced by the said electron beam.

2. A cathode ray tube and system comprising a tube having an electrically nonconducting base, an electrically nonconducting fluorescent screen on said base having a secondary electron emission ratio less than unity at electron beam velocities greater than 10,000 volts and a secondary electron emission greater than unity at a beam velocity lower than 10,000 volts, and an electron gun oppositely disposed from and wholly exposed to said screen, said gun comprising a cathode for generating an electron beam and an anode to focus said beam on said screen, a source of direct current potential exceeding 10,000 volts connected between said cathode and said anode to apply a difference of potential exceeding 10,000 volts and accelerate said electron beam to a velocity in excess of 10,000 volts, means to scan said electron beam over the surface of said screen, an auxiliary cathode adjacent and directly exposed to said fluorescent screen but outside the direct path between said electron gun and said screen, an auxiliary anode between said auxiliary cathode and said screen to direct a stream of electrons on the surface of said fluorescent screen along a path outside the path of said beam, and a

source of direct current potential of considerably less than 10,000 volts connected between said auxiliary cathode and said auxiliary anode to accelerate the electrons liberated by said auxiliary cathode and direct said electrons upon said screen at a velocity of bombardment under

which the said screen has a secondary emission ratio greater than unity and a luminescence only a fraction of the luminescence produced by the electrons from said first-mentioned cathode.

5

OTTO KLEMPERER.
